UNITED STATES PATENT OFFICE

140,064

DESIGN FOR A QUARTZ ORIENTATION TABLE UNIT

Danley Tilton, Los Angeles, Calif., assignor to
Robert H. Clark, Los Angeles, Calif.

Application March 17, 1944, Serial No. 112,942

Term of patent 3½ years

(Cl. D37—1)

To all whom it may concern:

Be it known that I, Danley Tilton, a citizen of the United States, residing in the city of Los Angeles, county of Los Angeles, and State of California, have invented a new, original, and ornamental Design for a Quartz' Orientation Table Unit, of which the following is a specification, reference being had to the accompanying drawings, forming a part thereof.

Fig. 1 is a perspective view of one side of a quartz orientation table unit showing my new design; and Fig. 2 is a perspective of the other side thereof.

I claim:

The ornamental design for a quartz orientation table unit, as shown.

DANLEY TILTON.
